ATTORNEYS

UNITED STATES PATENT OFFICE.

ELMORE CAVE, OF ST. LOUIS, MISSOURI.

WINDOW VENTILATOR.

Application filed February 16, 1923. Serial No. 619,445.

To all whom it may concern:

Be it known that I, ELMORE CAVE, a citizen of the United States, residing at St. Louis, Missouri, have invented a certain new and useful Improvement in Window Ventilators, of which the following is a full, clear, and exact description, such as will enable others skilled in the art to which it appertains to make and use the same.

10 This invention relates to window ventilators of the type that are adapted to be arranged in operative position in a window opening between the horizontal rail of one sash of the window and a horizontal portion 15 of the window frame.

One object of my invention is to provide an inexpensive ventilator of the kind referred to that can be adjusted easily to adapt it to windows of different widths and which 20 is so constructed that it will effectively ventilate a room without liability of rain beating into the room.

Another object is to provide a light-weight window ventilator that can be 25 shipped in knock-down form in a small container from the manufacturer of the ventilator.

And still another object is to provide a window ventilator that is equipped with an 30 air filtering device consisting of a piece of fabric, which is combined with the ventilator in such a manner that it can be easily disconnected from same when it becomes necessary to clean or wash the fabric to 35 move the particles of dust and dirt which the fabric collects from the air that circulates through the openings in the ventilator. Other objects and desirable features of my invention will be hereinafter pointed out.

40 Figure 1 of the drawings is an elevational view, looking at the inside of a window equipped with a ventilator constructed in accordance with my invention.

Figure 1^a is a perspective view, illustrating 45 one end portion of the ventilator arranged in operative position in the sash guide of the window frame.

Figure 2 is an edge view of the ventilator, taken on the section line 2-2 of Figure 1, 50 looking in the direction indicated by the arrows.

Figure 3 is a vertical sectional view, taken on the line 3-3 of Figure 1; and

Figure 4 is a rear elevational view of a

window ventilator constructed in accordance 55 with my invention and composed of three sections.

Referring to the drawings which illustrate the preferred form of my invention, A and B designate the top and bottom sash, respectively, of a window and C designates the frame of the window in which said sash are slidingly mounted, the side members of said frame having vertically-disposed guides that receive the side rails of the window 65 sash, as shown in Figure 1^a. My improved ventilator is of the type that is adapted to be arranged in the window opening between the horizontal rail of one window sash and a horizontal portion of the window frame 70 when said sash is partly open. The ventilator herein illustrated is of such construction that it is intended to be arranged between the lower rail 1 of the bottom sash B and the sill 2 of the window frame, with the end 75 portions of said ventilator projecting into the vertical guides in the side members of the window frame C that receive the bottom sash, as shown in Figures 1, 1^a and 3.

Said ventilator is composed of a plurality 80 of sections D constructed preferably of sheet metal and combined in such a way that they can be adjusted longitudinally relatively to each other to decrease or increase the length of the ventilator, thereby enabling the ventilator to be used in windows of different widths. It is immaterial how many sections the ventilator comprises, but it will usually be composed of two sections, as shown in Figure 1, or three sections, as 85 shown in Figure 4, combined in such a way that they are capable of being adjusted longitudinally relatively to each other and are capable of being taken apart easily, so

as to permit the ventilator to be shipped in knock-down form and packed in a relatively small container of substantially the same length as one of the sections of the ventilator. When the ventilator is composed of two sections each of said sections will comprise a vertically-disposed web 90

provided at its top and bottom edges and at its outer end with integral, laterally-bent portions 4 that form a rim which extends around three sides of said section, so that when the two sections are assembled the ventilator will have a practically continuous rim that extends around its marginal 105

2
edge. The sections of the ventilator are so proportioned and designed that the inner end portion of one section can be telescoped into the inner end portion of the adjacent section, thereby enabling the length of the ventilator to be varied easily by adjusting one section longitudinally relatively to the other. Various means can be used for connecting the sections together, but I prefer to provide the web 3 of one section, for example, the right hand section, with headed studs 5 and provide the vertical web of the other section with horizontally-disposed slots 6 through which the shanks of said studs 5 project, said slots having enlarged portions 6^a that are large enough to receive the heads of the studs 5, thereby permitting the sections to be assembled and disassembled easily by moving them longitudinally into such a position that the heads of the studs 5 on one section are in alignment with the enlarged portions 6^a of the slots 6 in the web of the other section.

The ventilator is provided at its upper edge with a vertically-disposed portion that laps over the inner side of the lower rail 1 of the bottom sash when the ventilator is in operative position, said upwardly-projecting portion being formed by vertical flanges 7 that project upwardly from the rim portions 4 at the top edges of the respective sections of the ventilator. If desired, the upwardly-projecting flange 7 and the bottom rim portion 4 on one of the sections, for example, the right hand section, can be doubled over at 7^a and 4^a, as shown in Figure 1^a, so as to form grooves in which the flange 7 and the bottom rim portion 4 of the left hand section can slide, thereby causing the flanges 7 and the bottom rim portions 4 of the two sections to be interlocked with each other. In assembling the sections of the ventilator the inner end portion of the left hand section D is inserted in the inner end portion of the right hand section in such a way that the vertically-disposed flange 7 and bottom rim portions 4 on said left hand section will be positioned in the grooves formed by the bent over portion 7^a and 4^a of the right hand section. The webs of the two sections are then spread apart sufficiently to permit the web of the left hand section to slide over the studs 5 until the enlarged portions 6^a of the slots 6 in the left hand sections come into alignment with the heads on said studs, thus permitting the webs to be forced together so as to cause the studs on the right hand section to enter the slots provided for same in the left hand section. Thereafter, one section is moved longitudinally of the other section so as to arrange the shanks of said studs in the slots 6.

The web 3 of each section of the ventilator 65 is provided with ventilating openings formed

preferably by louvres, each of which comprises a horizontally-disposed slot or opening 8 and an integral shield 9 at the upper side of said slot, as shown in Figure 3, that prevents rain from beating inwardly 70 through the slot, the louvres being formed by slitting the web of the section and then bending portions of said web outwardly. While I prefer to provide each section of the ventilator with a plurality of horizontally-disposed louvres, it will, of course, be understood that it is immaterial, so far as my invention is concerned, how the ventilating openings are formed or how they are arranged, so long as they are of such 80 design that rain cannot beat inwardly through the ventilator.

In order to prevent dust, dirt and the like from entering the room through the ventilating openings in the ventilator, the ventilator is equipped with an air filtering device, formed preferably by a piece of fabric E that is stretched over the inner side of the ventilator, as shown in Figures 3 and 4, and detachably connected to the ventilator 90 in such a way that it can be removed easily when it becomes necessary to clean said fabric. In the form of my invention herein illustrated the piece of fabric E is provided at its ends with strings or tying devices 95 that are adapted to be inserted through holes 11 in the end portions of the ventilator, for example, holes in the upwardly-projecting flanges 7 of the sections D and holes in the rim portions 4 of said sections that bear against the sill 2 of the window frame.

In arranging the ventilator in operative position the bottom sash B of the window is raised, as shown in Figure 1^a, and the ventilator is then positioned between said sash and the sill 2 of the window frame. One of the sections D of the ventilator is then moved longitudinally relatively to the other section, so as to cause the end portions of the ventilator to be positioned in the vertical guides in the side members of the window frame C that receive the side rails of the bottom sash B, and said bottom sash is then moved downwardly so as to 115 securely clamp the ventilator in operative position, with the upwardly-projecting flanges 7 at the top edge of the ventilator projecting upwardly over the inner side of the lower rail of the bottom sash. In order to permit the bottom sash B to be moved downwardly into engagement with the rim portions 4 at the top edge of the ventilator when the end portions of the ventilator are positioned in the sash guides in the window frame C, the vertical flanges 7 at the top edge of the ventilator are cut away at the ends of the ventilator, as shown in Figure 120 2, or are made a trifle shorter than the sections D of the ventilator.

A ventilator of the construction above described will not rattle when it is arranged in operative position in a window opening, due to the fact that it is clamped securely 5 between the bottom sash and the sill of the window frame, with the end portions of the ventilator positioned in the sash guides in the window frame, the vertically-disposed sash engaging portions 7 at the top edge 10 of the ventilator assisting in maintaining the ventilator in position and also forming a fairly tight joint between the ventilator and the portion of the bottom sash that bears upon same. Such a ventilator is 15 easy to install or remove from a window opening; it can be adjusted easily to adapt it to windows of different width; it is inexpensive to manufacture, as it is constructed from sheet metal sections that can 20 be formed by a simple stamping operation, and it is of light-weight and such design that it can be taken apart easily and shipped in knock-down form in a small container of substantially the same length as one section 25 of the ventilator. In addition to the desirable characteristics above pointed out it is equipped with an air filtering device that effectively separates or removes particles of dust and dirt in the air which circulates 30 through the ventilator, which filtering device is combined with the ventilator in such a way that it can be removed easily and

cleaned, thereby making the ventilator particularly adapted for household use.

Having thus described my invention, what 35 I claim as new and desire to secure by Letters Patent is:

A window ventilator consisting of a substantially oblong-shaped member of such dimensions that it can be arranged transversely of a window opening between the bottom sash and a horizontally-disposed portion of the window frame with its end portions positioned in the sash guides in said frame, said member being composed of a plurality 40 of sections that can be adjusted relatively to each other and each of which is formed from a sheet metal plate provided with slots and with integral shields arranged in proximity to said slots so as to prevent rain from 45 beating inwardly through the same, laterally-projecting flanges on said plates that co-operate with each other to form a rim at the top, bottom and ends of said member, a vertically-disposed flange on the top portion of 50 said rim that laps over the front face of the bottom rail of the sash and terminating short of the ends of said member, doubled over portions on one of said sections arranged in telescopic relation with co-operating portions on the other section, and slot 55 and pin connections between said sections.

ELMORE CAVE.
